UNITED STATES PATENT OFFICE.

ALBERT McDUGAL, OF NEW YORK, N. Y.

GOLF-CLUB HEAD.

1,291,967.

Specification of Letters Patent. Patented Jan. 21, 1919.

Application filed August 30, 1915. Serial No. 48,026.

To all whom it may concern:

Be it known that I, ALBERT McDUGAL, a citizen of the United States, residing at New York, in the county of New York and 5 State of New York, have invented new and useful Improvements in Golf-Club Heads, of which the following is a specification.

This invention relates to golf clubs and particularly to a head for a device of this 10 class, and one object of the invention is to provide the head of what is known as a "putter" with means whereby the player is materially assisted in determining the line to the hole through the medium of a true 15 line parallel to the face of the club head intersecting a line parallel to the hole, and whereby a player will be enabled to more accurately line up the putt. A further object of the invention is to provide means in 20 connection with a golf club head that is always ready for use, without requiring adjustment, to enable a player to direct the fly of the ball or in properly addressing the ball, and whereby also the necessary angle of 25 direction of movement of the ball may be easily determined in making various plays.

With these and other objects and advantages in view the invention consists in the preferred construction and arrangement of 30 parts which will be more fully hereinafter described and claimed.

In the drawing:

Figure 1 is a perspective view of a portion of a golf club showing the head of the 35 type known as a putter and embodying the features of the invention.

Fig. 2 is a central transverse vertical section through the head as shown by Fig. 1.

The numeral 5 designates a golf stick or 40 club having a head 6, which as shown is of the putter type and provided with a straight driving face or edge 7. The top surface of the head 6 is horizontally flat, or approximately so, and said head is provided with an 45 indicating means or device 8 parallel with the face or edge 7. The means or device 8 is intersected at right angles by a transversely arranged similar means or device 9, the two means or devices 8 and 9 being fixed 50 in their application to the head and fully exposed to the player, the said means or devices 8 and 9 also having a marked distinguishing characteristic and of such dimensions as to be readily discerned by the player. 55 It is preferred that the means or devices 8

and 9 be composed of hard rubber strips inset in the upper portion of the head 6 by a dovetail construction or by forming dovetail recesses 10 and 11 and correspondingly constructing the strips of hard rubber and insetting said strips in the grooves so that their upper surfaces will be flush with the upper surface of the head 6. If the hard rubber devices or strips 8 or 9 be black, it is 60 obvious that they can be readily seen by the player. It will also be understood that they may be of other distinguishing shades, such as blue, red or white. The width of the devices or strips 8 and 9 may be varied as desired, but in length it is preferred that the 65 device or strip 8 extend almost wholly along and in parallel relation to the edge 7 and that the device or strip 9 continue completely from the device or strip 8 fully to the rear edge of the head 6 and centrally positioned 70 in relation to said head.

By means of the sighting or directing devices in connection with the head 6 as shown, a player is materially assisted in causing the ball to fly as may be desired in view of the 80 fact that the proper angle or necessary direction of movement may be accurately determined, for the reason that the player has a true line parallel to the face or edge 7 and also another true line at right angles to the 85 first named line that may be disposed in line with the hole, and as a consequence the player will be guided in striking the ball to cause the latter to fly in the direction of the hole. The difficulty heretofore experienced 90 with putter heads commonly used, was that no assistance was given the player in finding the line to the hole. By having a true line parallel to the face of the club together with an intersecting line parallel to the hole enables a player to be more accurate in lining up the putt. Instead of using hard rubber in forming the devices or strips embodying the features of the improvement it will be 95 understood that fiber or any other suitable substance may be adopted. Moreover, the improved features may be readily applied to an ordinary golf club head and particularly of the character specified without affecting the reliable playing service of the 100 head, it only being necessary to groove the upper portion of the head to secure the improved directing means in place therein. The simplicity of the improved golf club head also renders it possible to easily equip 110

golf club heads already in use with the intersecting angular devices embodying the features of the invention.

What is claimed is:

- 5 1. A golf club head having an upper flat surface and a straight addressing edge, and a T-square indicating means having a fixed application to the said flat surface, the base of the square being parallel with the addressing edge and the remaining part of the square extending over the transverse center of the head at right angles to the addressing edge.
- 10 2. A golf club head having an upper flat surface and a straight addressing edge, and a T-square indicating means having a fixed

application to the said upper surface of the head and consisting of strips inlaid in the head, the base strip of the square being located inwardly a distance from and parallel 20 to the addressing edge, and the remaining strip extending over the transverse center of the head at right angles to the addressing head.

In testimony whereof I have hereunto set 25 my hand in presence of two subscribing witnesses.

ALBERT McDUGAL.
